United States Patent Office

Des. 212,623
Patented Nov. 5, 1968

212,623

TABLE

Morris B. Rubenstein, 7 Southwind,
Hampton, Va. 23369

Filed May 19, 1967, Ser. No. 7,198

Term of patent 14 years

(Cl. D33—14)

FIG.1

FIG. 2

FIG.3

FIG.4

FIG.5

Fig. 5

FIGURE 1 is a perspective view of a table showing my design;

FIGURE 2 is a side elevation view;

FIGURE 3 is a top plan view;

FIGURE 4 is a bottom plan view;

FIGURE 5 is a bottom plan view of a modified embodiment of the invention wherein the legs are arranged diagonally of the table top; and

FIGURE 6 is a perspective view of the modified embodiment of the invention illustrated in FIGURE 5.

I claim:

The ornamental design for a table, as shown.
